UNITED STATES PATENT OFFICE

WILLIAM LEIDEL, OF ELMHURST, NEW YORK

TOILET ACCESSORY

Application filed June 14, 1930. Serial No. 461,079.

This invention relates to improvements in toilet accessories, and more particularly to toilet accessories for carrying and dispensing loose powder for personal purposes.

Among the principal objects the invention has in view are: to provide an improved loose powder container and means for readily dispensing the powder; to provide means whereby a limited amount of loose powder is released from the container at one time; to provide means for fully closing the dispenser when no powder is to be used; to provide a dispensing container which will not leak; to secure simplicity of construction and operation; and to obtain other advantages and results as may be brought out in the following description.

Drawing:

Figure 1 is a view looking down at a loose powder container, with the cover open, and embodying my invention;

Figure 2 is a sectional view, shown as taken on the line 2—2 of Figure 1;

Figure 3 is a sectional view, shown as taken on the line 3—3 of Figure 1;

Figure 4 is a sectional view, shown as taken on the line 4—4 of Figure 1;

Figure 5 is a sectional view, shown as taken on the line 5—5 of Figure 2;

Figure 6 is a longitudinal sectional view of the roller;

Figure 7 is a view similar to Figure 1, wherein is shown my invention in modified form;

Figure 8 is an edge view of the powder box removed from the container;

Figure 9 is a longitudinal sectional view, shown as taken on the line 9—9 of Figure 7;

Figure 10 is a sectional view, shown as taken on the line 10—10 of Figure 9; and

Figure 11 is an enlarged sectional view of the roller.

In the specification:

In one specific embodiment of the invention illustrated in said drawing, and referring more particularly to Figures 1 to 6, the reference numeral 10 indicates a loose powder container, with a cover or lid 11 connected to the container by suitable hinging means

12, so the lid may be opened and closed as desired.

In carrying out my invention, I preferably provide a circular member or pan 13, having a peripheral flange 14. Said flange permits the pan 13 to snugly fit within the container 10, and likewise permits accessibly removing the pan for refilling the container with powder as it becomes exhausted.

Within the pan and transverse thereof, I have provided an opening 15 substantially the width of the interior of said pan. Extending longitudinally of and partly within said opening 15, is a roller 16 which is shown substantially triangular in cross-section, one side of said roller being flat, so as to be substantially in the same plane as the pan when no powder is to be dispensed from within the container.

The other two sides of the triangular roller are provided with means to pick up powder from within the container, said means are

preferably in the form of longitudinal grooves 17 which form pockets for the powder to lodge in. When powder is desired, the roller is turned one way or the other until one groove or pocket with powder therein is exposed at the upper face of the pan 13

after which a powder puff (not shown) is saturated with the powder. Should more powder be desired, a second operation similar to the first is repeated.

For mounting the roller, I have provided means on both ends thereof in the form of pins 18, 19, one of which is secured to the downwardly projecting wall of the pan as at 20; the other pin 19 being somewhat longer extends out through the wall of the pan and casing and has affixed thereto, a knurled stem 22. Said stem permits readily rotating the roller 16 from outside the container 10 and pan 13.

To prevent the roller from having too much freedom of movement, I have provided on the inside face of the stem and adjacent the container, a plurality of detents or notches 23 as clearly shown in Figure 5.

These detents or notches are provided to permit a lip or small projection 24 of the container to engage therein as seen in Figures 2 and 4 of the drawing.

To make the engagement of the lip 24 with

the notches 23 of the stem 22, more positive, I have made a slit 25 in the frame of the container 10, and by so doing obtain a flexible strip which provides desired resiliency to permit the lip to more freely engage and disengage with one of the notches in the stem.

To refill the powder container, the pan must first be removed, and in order to do that, I have cut away a portion of the outside 10 container to form a straight slot 26. Said slot at its lower end permits the pin 19 to rest therein. When removing the pan, it is lifted upwardly through the open end of the slot, and the container may then be refilled 15 with powder, after which the pan is again reset in place.

To prevent powder from caking on the pan 13, I have provided the inside rim of said pan with rounded or filet edges 28. It 20 will be noted that by having the rim rounded, no loose powder which may escape from a puff will be able to fill in and thus become caked, thereby making it difficult to remove.

While I have described the invention in 25 detail and particularly adapted for use in circular containers, I do not wish it understood that I am limiting myself to that specific structure, as containers of other shapes and designs may likewise be used. As an 30 other form of container, I now refer to Figures 7 to 11 wherein the invention is adapted to a container square in shape of the vanity box type, and having rouge and lip stick compartments, also a nickel mirror to 35 separate the rouge from the loose powder pan.

In carrying out the invention, the reference numeral 27 indicates the box in its entirety and having a mirror 28 suitably attached to the securing or hinged portion 29. In the cover or lid 30 is provided a cake of rouge 31 and a well or opening 32 for inserting a lip stick holder.

The lower part or body portion 33 is provided 40 with a pan 34 having a powder dispenser or roller 35 inserted therein and preferably positioned towards the lower end thereof. Said pan 34 may be removed when necessary to refill the powder chamber 36 of 45 the body portion.

To operate the roller so that powder may be removed therefrom, I have provided a sliding member 37 on the upper surface of the container and independent of the pan 34. 50 When powder is desired, the sliding member is pushed downward until the edge thereof registers with the configuration OP. When no powder is to be dispensed, the sliding member is pushed back until it registers with the configuration CL. When the pan is to be removed for purposes of refilling, the powder chamber, the sliding member is then adjusted until it registers with the configuration FL.

55 In carrying out the invention, the sliding

member 37 has affixed thereto a flat spring member 38 and provided towards its forward end with an opening 39 to permit easily removing the pan from the container. On the underside of the sliding member and spring member is provided a sliding arm 40 which is laterally disposed towards its forward end and extends downwardly a sufficient distance and then projects forward longitudinally. Said longitudinal portion has a slot 41 therein for a rocker pin 42 from the roller 35, to ride within. When the sliding member 37 is worked backward or forward, as the case may be, the sliding arm 40 moves simultaneously therewith.

The roller 35 is provided at its opposite ends with pins 43 and 44 respectively. The pin 43 being secured to the downwardly extending wall 45 of the pan 34 and the other pin 44 extends out through the pan wall and casing of the container, the end thereof being turned downwardly to form the rocker portion 42, said portion resting within the slot 41 of the movable arm 40.

The roller 35 in this instance is preferably 90 constructed of sheet metal with its ends twined downwardly, as at 46 and 47, to prevent any loose powder from entering through the ends. The roller is then stamped out to form a flat surface on one side, said flat surface being on substantially the same plane as the pan, so that when no powder is to be dispensed this flattened surface of the roller will make a complete closure for the opening to 95 keep the powder within the powder chamber and prevent any powder from leaking. The other side of the roller is rounded so as to sweep or scoop powder into a hollowed portion 48 of the roller. When the powder in 100 said hollowed portion of the roller is to be used the working mechanism heretofore described is put into operation so as to turn said hollowed portion upward at the exposed face of the pan.

Claim:

1. A toilet accessory comprising a container with an enclosure having an outer surface from which powder may be wiped, a slot extending longitudinally and substantially the diameter of the enclosure, a roller fitted within said slot, and means for retaining said roller within the enclosure, said roller being triangular in shape and provided with longitudinal grooves on two sides for dispensing a measured quantity of powder from 115 within said enclosure to the outer surface of said enclosure, and the other side of said roller being substantially flat to register with the outer surface of the enclosure to prevent seepage of powder through the slot when not in use.

2. A toilet accessory comprising a container with an enclosure having an outer surface from which powder may be wiped, a slot extending longitudinally and substantially 120

the diameter of the enclosure, a roller fitted within said slot, and means for retaining said roller within the enclosure, said roller being triangular in shape and provided with longitudinal grooves on two sides for dispensing a measured quantity of powder from within said enclosure to the outer surface of said enclosure, and the other side of said roller being substantially flat to register with the outer surface of the enclosure to prevent seepage of powder through the slot when not in use, and a stem on the outside of said container to rotate the roller within the container.

3. A toilet accessory comprising a container with an enclosure having an outer surface from which powder may be wiped, a slot extending longitudinally and substantially the diameter of the enclosure, a roller fitted within said slot, and means for retaining said roller within the enclosure, said roller being triangular in shape and provided with longitudinal grooves on two sides for dispensing a measured quantity of powder from within said enclosure to the outer surface of said enclosure, and the other side of said roller being substantially flat to register with the outer surface of the enclosure to prevent seepage of powder through the slot when not in use, and a stem on the outside of said container to rotate the roller within the container, and said stem being provided with means to prevent too rapid movement of the roller when powder is to be dispensed to the surface of the enclosure.

4. A toilet accessory comprising a container with an enclosure having an outer surface from which powder may be wiped, a slot extending longitudinally and substantially the diameter of the enclosure, a roller fitted within said slot, and means for retaining said roller within the enclosure, said roller being triangular in shape and provided with longitudinal grooves on two sides for dispensing a measured quantity of powder from within said enclosure to the outer surface of said enclosure, and the other side of said roller being substantially flat to register with the outer surface of the enclosure to prevent seepage of powder through the slot when not in use, and a stem on the outside of said container to rotate the roller within the container, said stem being provided with means to prevent too rapid movement of the roller when powder is to be dispensed to the surface of the enclosure, and means on the outside of the container adjacent said means on the stem to register therewith when turning the stem.

5. A toilet accessory comprising a container with an enclosure having an outer surface from which powder may be wiped, a slot extending longitudinally and substantially the diameter of the enclosure, a roller fitted within said slot, and means for retaining said roller within the slot, said roller having a

longitudinal groove on one side thereof for dispensing a measured quantity of powder from within said enclosure, the other side of said roller being substantially flat to register with the outer surface of the enclosure to prevent seepage of powder through the slot when not in use, and means on one end of said roller to rotate the roller when in operation.
